US00D741862S

(12) **United States Design Patent**
Beroukhim et al.

(10) **Patent No.:** **US D741,862 S**
(45) **Date of Patent:** **** Oct. 27, 2015**

(54) **PORTABLE BIOMETRIC SCANNER**

(71) Applicant: **NEC Corporation**, Tokyo (JP)

(72) Inventors: **Fariborz R. Beroukhim**, Los Angeles, CA (US); **John B. Dowden**, Pasadena, CA (US); **Hideo Abe**, Yokohama (JP); **Hiroshi Takeba**, Yokohama (JP); **Travis S. Cochran**, Costa Mesa, CA (US); **Jonathan R. Lucas**, Long Beach, CA (US); **Sam Iravantchi**, Fountain Valley, CA (US); **Yukinobu Kimoto**, Tokyo (JP)

(73) Assignee: **NEC Corporation**, Tokyo (JP)

(**) Term: **14 Years**

(21) Appl. No.: **29/502,573**

(22) Filed: **Sep. 17, 2014**

(57) **CLAIM**

The ornamental design for a portable biometric scanner, as shown and described.

DESCRIPTION

FIG. 1 is a perspective view of the scanner;

FIG. 2 is a front view of the scanner;

FIG. 3 is a left side view of the scanner;

FIG. 4 is a right side view of the scanner;

FIG. 5 is a top view of the scanner;

FIG. 6 is bottom view of the scanner; and,

FIG. 7 is a rear view of the scanner.

The broken lines shown in the drawings represent portions of the portable biometric scanner that form no part of the claimed design.
